CLAIM

The ornamental design for a lid, as shown and described.

DESCRIPTION

FIG. 1 is a top, front, right perspective view of a lid showing our new design;

FIG. 2 is a front view thereof;

FIG. 3 is a rear view thereof;

FIG. 4 is a right side view thereof;

FIG. 5 is a left side view thereof; and

FIG. 6 is a top view thereof; and,

FIG. 7 is a bottom view thereof.

The broken lines immediately adjacent to the shaded area represent unclaimed boundaries of the design. The bracketed portion shown in FIGS. 1–5 showing a break in the surface represents indeterminate length and forms no part of the claimed design. The broken lines showing the remainder of the lid are for environmental purposes only and form no part of the claimed design.
